US0D1023115S

(12) **United States Design Patent** (10) Patent No.: **US D1,023,115 S**
(45) Date of Patent: ** Apr. 16, 2024

- (54) **CAMERA MOUNT**
(71) Applicant: **GoPro, Inc.**, San Mateo, CA (US)
(72) Inventors: **Nicholas Vitale**, Foster City, CA (US);
John George Muhlenkamp, IV,
Brisbane, CA (US); **Huy Phuong**
Nguyen, Alpine, UT (US); **Marco**
Marroquin, San Mateo, CA (US);
Nicholas D. Woodman, Big Sky, MT
(US)
(73) Assignee: **GoPro, Inc.**, San Mateo, CA (US)
(**) Term: **15 Years**
(21) Appl. No.: **29/890,568**
(22) Filed: **Apr. 25, 2023**
